CLAIM

The ornamental design for a magazine catch for a firearm, as shown and described.

DESCRIPTION

FIG. 1 is a first perspective view of the magazine catch for a firearm according to the present design;

FIG. 2 is a second rotated perspective view of the design of FIG. 1;

FIG. 3 is a front plan view of the design of FIG. 1;

FIG. 4 is a rear plan view of the design of FIG. 1;

FIG. 5 is a right side view of the design of FIG. 1;

FIG. 6 is a left side view of the design of FIG. 1;

FIG. 7 is top view of the design of FIG. 1; and,

FIG. 8 is a bottom view of the design of FIG. 1.

The broken line in the drawings discloses the unclaimed portions of the magazine catch for a firearm only and forms no part of the claimed design.
